CLAIM

The ornamental design for a combined beverage dispenser and service module, as shown and described.

DESCRIPTION

FIG. 1 is a front elevational view of a combined beverage dispenser and service module showing my new design;

FIG. 2 is a right side elevational view thereof;

FIG. 3 is a left side elevational view thereof;

FIG. 4 is a rear elevational view thereof; and,

FIG. 5 is a sectional view thereof, the top being incorporated in the building environment and the bottom plan view being plain and unornamented.

The broken line showing of the upper portion of the column in FIGS. 1-4 is for illustrative purposes only and forms no part of the claimed design.

FIG-1
